ABRADING APPARATUS

Walter L. Keefer, Hagerstown, Md., assignor to Pangborn Corporation, Hagerstown, Md., a corporation of Maryland

Original application March 10, 1938, Serial No. 195,138, now Patent No. 2,246,522, dated June 24, 1941. Divided and this application June 21, 1941, Serial No. 399,185

19 Claims.

(Cl. 51—9)

This invention relates to abrading apparatus and is more particularly concerned with machines embodying a bladed rotor for propelling abrasive at high velocity against articles to be cleaned. Such machines in their basic form comprise a rotor, a feed spout for abrasive, and transfer mechanism for transferring the abrasive from the feed spout to the rotor.

This application is a division of my application Serial No. 195,138, filed March 10, 1938, for Abrading apparatus now Patent No. 2,246,522.

Machines embodying bladed rotors are in commercial use today which, although they represent an advance in the art over machines used heretofore, leave much to be desired from the standpoint of wear of various essential operating parts. For instance, directional control is attained in those machines through the use of a central stationary feed cage having a feed slot therein through which abrasive is discharged onto the inner ends of the blades by means of a rotatable impeller located in the feed cage. These impellers and cages wear out comparatively rapidly under the action of the abrasive, and must be removed and replaced by new parts, which entails the expense of the new parts, and also the loss of operating time that is involved while the machine is shut down or dismantled for servicing. In my United States Patent No. 2,116,153, granted May 3, 1938, I have shown a bladed centrifugal abrading machine which possesses directional control, and yet which does not employ an impeller, or a slotted stationary feed cage, and it is the major object of this invention to improve and generally refine such machines.

A further object is to provide a bladed centrifugal abrading machine including a transfer mechanism comprising a rotatable abrasive accumulating cup and a stationary helical deflecting member for deflecting the abrasive from the cup onto the blades.

It is another object to provide a centrifugal abrading machine with a transfer mechanism comprising a combined abrasive feeder and deflecting assembly for cooperation with a rotary cup of a bladed centrifugal abrading rotor.

A further object is to provide a bladed abrading rotor with a central rotary chamber or cylinder which is spaced from the rotor and receives the abrasive at one end and discharges the abrasive onto the inner ends of the blades from the other end of the feed chamber.

Further objects will become apparent as the specification proceeds in connection with the annexed drawings, and from the appended claims.

In the drawings,

Figure 1 is a longitudinal section of a portion of an abrading apparatus embodying the present invention.

Fig. 2 is a front elevational view of the rotor shown in Fig. 1 with the feed spout and deflector assembly removed and the abrasive chamber shown in section on the line 2—2 of Fig. 1.

Fig. 3 is a fragmental section taken substantially on the line 3—3 of Fig. 2.

Fig. 4 is a longitudinal section of a further modified form of abrading apparatus embodying this invention.

Fig. 5 is a front elevation of the rotor of Fig. 4 with the feed spout and deflector removed and the feed chamber taken in section on the line 5—5 of Fig. 4.

Fig. 6 is a diagrammatic development of a portion of the abrasive chamber and a portion of the deflector of Fig. 4.

Fig. 7 is a front elevation of the feeding side of a further modified form of the invention.

Fig. 8 is a longitudinal section taken vertically through the axis of the device shown in Fig. 7.

Fig. 9 is a fragmental section taken substantially along the line 9—9 of Fig. 8, and

Fig. 10 is a fragmental section taken on the line 10—10 of Fig. 9, the section being turned through an angle of 90°, the deflector assembly being omitted to more clearly illustrate the remaining structure.

Referring to Figs. 1 to 3, inclusive, the rotor including the blade assembly may assume any desired form. For the purpose of illustration, I have shown a rotor R secured to a hub portion 10 of a shaft 11 by means of a plurality of screws (not shown). A plurality of sector-shaped plates 12 are detachably secured to the face of rotor R by a plurality of screws 13.

As shown in more detail in Fig. 3, plates 12 are spaced apart on the face of the rotor and their neighboring edges are beveled as at 14 so that they cooperate with the face of the rotor to define outwardly extending dovetail-shaped grooves. Blades B are provided with correspondingly dovetail-shaped bases 15 which are received in the above-mentioned grooves. The blades are preferably locked against outward movement by a plurality of detachable keys of the type shown in my above-identified application; these keys slidably fitting in correspondingly shaped openings provided in plates 12.

Each blade B is provided with an abrasive propelling face 16 and an abrasive guiding flange 17 for preventing the abrasive from escaping over the free edge of the blade during operation.

The rotor R may be made to extend wholly across the face of the hub 10, or it may be formed with a central opening which is closed by a wear plate 18 secured in place by a cap screw 19. The transfer mechanism includes an abrasive chamber or cylinder 21 which is positioned between the inner ends of blades B with its axis preferably in alignment with the axis of shaft

11, and is provided with a discharge edge 22 located approximately medially with respect to the width of the blades. The other end of the chamber is provided with a preferably flanged or conical wall 23 for preventing the inadvertent escape of abrasive from the feed chamber.

Abrasive is supplied to the apparatus by means of a feed spout 24, the third element of the machine, which is stationarily supported in any suitable manner, the lower end thereof being provided with a boss 25 to which a deflector assembly D is secured by a cap screw 26. Deflector assembly D is provided with a helical deflecting flange 27 of increasing radius toward discharge edge 22.

Chamber 21 may be secured to rotor R in any suitable manner. For instance, it may be carried by plates 12, if desired. In Figs. 2 and 3, I have illustrated the chamber as provided with a plurality of arms 31 which are disposed so as to lie closely behind blades B.

A plurality of studs 32 are provided with reduced portions 33 which are threaded into the plates 12. Studs 32 are also provided with reduced portions 34 which pass through openings in the outer ends of arms 31. Nuts 35 are threaded on stud ends 34 and firmly clamp arms 31 into position thereon. Chamber 21 is accordingly rigidly supported on rotor R, and as studs 32 are disposed rearwardly of each blade, they are subjected to only a minimum abrading action, especially since the abrasive issuing from the chamber is not traveling at a velocity high enough to effect any substantial abrading. If a two disc form of rotor is used, chamber 21 may be secured directly to the lefthand disc.

In operation, spout 24 is supplied with abrasive in any suitable manner, preferably metered, and from a gravity drop to impart the desired initial velocity to the abrasive. The abrasive fed into the spout is discharged upon the inner wall of chamber 21, and is quickly picked up and promptly brought up to the full peripheral speed of the inner wall of the chamber. After a pre-determined quantity of abrasive has accumulated in chamber 21, it builds up therein to its angle of repose which will face discharge edge 22 because of wall 23. If the feed of abrasive into the chamber be arrested at this point, the abrasive will remain on the inside wall of the chamber and will not discharge over edge 22.

As described, deflector D comprises a flange 27 which is preferably so shaped that its outer periphery generally conforms to the surface of the cone-shaped layer of abrasive lying in the chamber, and is accordingly a helix of increasing radius toward discharge edge 22 of the chamber. Flange 27 is preferably beveled at its outermost edge to substantially conform with the angle of repose of the abrasive lying in the chamber, and preferably extends for approximately three quarters of a revolution, or 270°, with the result that the abrasive starts to undergo an axial deflection towards discharge edge 22 at a point 28, and is finally deflected over the discharge edge of the chamber when it reaches point 29.

If desired, deflector D may be provided with a substantially cylindrical flange adjacent discharge edge 22, which flange has little, if any, "pitch," and which may be termed a splash deflector, as described in my above-identified application. Such a flange would lie substantially in the plane of discharge edge 22 and function to prevent abrasive which may inadvertently or pre-

maturely be started down the incline from discharging over the edge of the chamber before the proper discharge point is attained. As described in my above-identified application, such a flange preferably terminates short of point 29 to permit the abrasive to leave the cup at that point. The abrasive lying on the interior of the chamber is accordingly deflected over the edge thereof at a predetermined point in the rotation of the wheel, and stray abrasive is prevented from leaving elsewhere by the splash deflector.

Deflector D in Fig. 1 is shown as being adjusted to cause the abrasive to be dislodged from the edge of the feed chamber at approximately the twelve o'clock position. The abrasive is thrown substantially tangentially by reason of the fact that it possesses substantially no radial velocity, and is traveling at the peripheral speed of the chamber at the instant of discharge. The discharge from edge 22 accordingly assumes the form of a slightly fan-shaped, continuous ribbon which is cut by the inner ends of the blades as they successively pass through it. It is also apparent that as the abrasive discharging from the chamber is traveling in the same general direction as the inner ends of the blades, it is picked up with a minimum impact. The abrasive picked up is smoothly and continuously accelerated by the blades, and is discharged from the outer ends thereof in a downward direction.

It has been found in practice that all of the parts of the deflector assembly function cool in operation, and wear thereon is slow. Deflector flange 27 serves to initially discharge the abrasive. Because its outer periphery forms a cone of increasing radius in the direction of the discharge edge, the abrasive is caused to tend to continue more down the incline. The full length of flange 27 controls the movement of the abrasive across the conical surface until it is finally discharged at edge 22. Wear on the flange is slow because the major force impelling the abrasive toward the discharge edge is supplied by centrifugal force, and the flange only exerts a minor or light following action upon the abrasive.

In Figs. 4, 5, and 6, I have illustrated an abrading apparatus similar to that just described, but it involves a chamber which is completely closed except for the feed opening and an opening for each blade.

In Figs. 4, 5, and 6, rotor R is provided with blades B in accordance with the previously described form of the invention. A chamber 36 having an end opening 31 is secured in the central space between the inner ends of the blades by means of a plurality of cap screws 38 which pass through lugs 39 provided on the outside of the cage. At its left end, chamber 36 is provided with a removable flange 36' suitably fastened by screws as shown to permit the insertion and removal of the combined feed spout and deflector assembly. The combined feed spout and deflector assembly extends through the open end of the feed cage and is provided with a spout portion 41 to which abrasive is supplied, and which discharges inside of the chamber. Formed on the outside of the deflector assembly is a helical deflector flange 42 which terminates adjacent the left end of the chamber. The chamber is provided with a plurality of openings 43 forwardly of each blade B, and through which the abrasive deflected by member 42 is discharged. As seen in Fig. 4, spout 41 discharges the abrasive into chamber 36 between deflector

members 42 and 44, the latter being preferably a flange of substantially no pitch extending only part way around the deflector assembly.

The abrasive deflected by member 42 is accordingly successively discharged through openings 43 in front of each blade as the blade passes a predetermined point in the rotation of the rotor, and the machine accordingly effects a restricted discharge of the abrasive in a manner similar to the apparatus shown in Figs. 1 and 2. Flange 44 prevents abrasive from inadvertently or prematurely splashing into the discharge ports 43. Deflector flange 42 is preferably made of increasing radius toward discharge ports 43 in much the same manner as flange 27 of Fig. 1.

In Fig. 6, I have illustrated the interior of the chamber and a portion of deflector flange 42 in developed form to illustrate the manner in which the abrasive is progressively propelled toward discharge ports 43, and successively discharged therethrough onto the inner ends of the blades.

It is to be understood that the term "discharge edge", as employed in the description and appended claims applies to discharge edge 27 of the embodiment shown in Figs. 1 to 3, inclusive, and also to discharge ports 43 of the form of the invention shown in Figs. 4 to 6, inclusive.

In Figs. 7 to 10, inclusive, I have shown a form of feeding assembly somewhat similar to those shown in Figs. 1 to 6, with the exception that a major portion of a chamber 50 is located outside the central space defined by the inner ends of the blades, and the chamber and the deflector assembly are secured in place in a different manner. The rotor and blade construction is generally the same as that shown in Fig. 1, and fitting within a central opening 45 in the rotor and secured to hub 10 through a spacer disc 46 and cap screws 47 is a flange portion 48 of a shaft or support 49.

The chamber is generally cylindrical and is provided with a discharge edge 51 as in the other forms of the invention. The rear end of the chamber is partially closed by a flange 52 to minimize abrasive leakage, and to enable the abrasive to be built up to its angle of repose. Projecting inwardly from the inner wall of chamber 50 are a plurality of supports 53 which generally assume the form of blades, the supports being joined in the center by a disc portion 55 which is secured to the end of shaft 49 by a cap screw 56.

The chamber is accordingly mounted for positive rotation with the rotor and abrasive is fed thereto by means of a feed spout 57 having a curved lower end projecting into the opening provided by flange 52.

The abrasive is adapted to be deflected from the inner wall of the chamber in much the same manner as previously described in connection with the other embodiments of the invention. A deflector assembly 58 is provided with a central opening 59 through which shaft 49 extends. Secured to a pair of arms 61 on support 62 by means of bolt and nut assemblies 63 is a flange 64 of deflector 58. Support 62 extends through housing 65 and liner 66 and is provided with a flange 67 having a pair of arcuate openings 68. A pair of studs 69 are secured to housing 65 and project through openings 68. Nuts 71 are threaded thereon for adjustably clamping flange 67 to the housing. By loosening nuts 71, the deflector assembly may be rocked so as to vary the direction of discharge. It is to be understood that the previously described forms of the invention may also be provided with such adjustment means.

The deflector assembly functions in a manner similar to those previously described and embodies a helical deflecting member 72 of increasing radius for dislodging, or deflecting, the abrasive from the chamber, and for causing it to discharge, as indicated by arrows 73 in Fig. 10, onto the inner ends of the blades at a predetermined point in the rotation of the rotor. With the parts adjusted as shown, the machine will discharge downwardly, but it may be adjusted to discharge in any desired direction.

If it is desired to further restrict the width of discharge stream from the rotor, a stationary guard 74 may be provided to cooperate with the discharge from the chamber, as shown in Fig. 10, to prevent any prematurely discharging abrasive, indicated by arrows 75, from entering the blades in other than the proper pick-up zone. Guard 74 is provided with a support 76 which is secured to one of arms 61 by means of nut and bolt assemblies 63.

It is to be understood that certain features of the various forms of the invention may be used with, or substituted for, certain features of other forms of the invention. For instance, if desired the discharge edge of the chamber in the form of the invention last described may be provided with openings or ports, as shown in Figs. 4, 5, and 6, without departing from the spirit of the invention.

It is to be understood that the invention may be embodied in specific forms other than that illustrated without departing from the principle or essential characteristics thereof. The embodiments shown are therefore to be considered as illustrative and not restrictive, the scope of the invention being defined by the appended claims rather than the foregoing description and drawings. All modifications and changes which come within the meaning and range of equivalency of the claims are therefore intended to be included therein.

I claim:

1. In an abrading apparatus, a rotor having a plurality of outwardly extending abrasive propelling blades of a length to dispose their outer ends sufficiently radially distant from the axis of the rotor to propel the abrasive at an abrading velocity, a centrally disposed chamber having a substantially cylindrical wall to provide a substantial capacity for abrasive relative to the angle of repose and mounted for synchronous rotation with said rotor, and having an inner wall of a relatively small diameter so that abrasive thereon travels at less than an abrading velocity, means for supplying abrasive into an outer end of said chamber, and stationarily supported means having a helical surface for causing abrasive accumulating in said chamber to be moved towards the inner end of the chamber and discharged from said chamber onto said blades adjacent the inner ends thereof at a predetermined point in the rotation of said rotor, said helical surface increasing in radius as it approaches the discharge end of said chamber, said rotor comprising at least one disc mounted on a shaft, and said chamber being located between said disc and the point at which abrasive is delivered into said feed chamber.

2. In an abrading apparatus, a rotor having a plurality of outwardly extending abrasive propelling blades of a length to dispose their outer ends sufficiently radially distant from the axis of the rotor to propel the abrasive at an abrading velocity, a centrally located end substantially cy-

lindrical chamber mounted for rotation with said rotor substantially concentric of the axis of said rotor, one end of said chamber terminating adjacent said blades to constitute a discharge edge for abrasive, means to feed abrasive into the opposite end of said chamber and allow it to build up centrifugally on the inner surface thereof, and means for deflecting a portion of the accumulated abrasive from the chamber onto said blades adjacent the inner ends thereof at a predetermined point in the rotation of said rotor.

3. In an abrading apparatus, a rotor having a plurality of outwardly extending abrasive propelling blades, a centrally located and substantially cylindrical chamber mounted for rotation with said rotor substantially concentric of the axis of said rotor, one end of said chamber terminating adjacent said blades to constitute a discharge edge for abrasive, the opposite end of said chamber having an inwardly tapered wall to define a portion of a hollow cone whereby abrasive collected against the inner wall of said chamber will build up to an angle of repose facing the discharge end of said chamber, means to feed abrasive into the tapered wall end of said chamber and allow it to build up centrifugally on the inner surface thereof, and means for deflecting a portion of the collected abrasive from said chamber onto said blades adjacent the inner ends thereof at a predetermined point in the rotation of said rotor.

4. In an abrading apparatus, a rotor having a plurality of outwardly extending abrasive propelling blades of a length to dispose their outer ends sufficiently radially distant from the axis of the rotor to propel the abrasive at an abrading velocity, a centrally located and substantially cylindrical chamber mounted for rotation with said rotor substantially concentric of the axis of said rotor, one end of said chamber terminating adjacent said blades to constitute a discharge edge for abrasive, a stationary feed spout to feed abrasive into the opposite end of said chamber, and means mounted on said feed spout for deflecting a portion of the accumulated abrasive from the chamber onto said blades adjacent the inner ends thereof at a predetermined point in the rotation of said rotor.

5. In an abrading apparatus, a rotor having a plurality of abrasive propelling blades provided thereon, a centrally located chamber mounted for synchronous rotation with said rotor, means for introducing abrasive into said chamber and allowing it to build up centrifugally on the inner surface thereof, means for deflecting a portion of the accumulated abrasive from the chamber onto said blades adjacent the inner ends thereof at a predetermined point in the rotation of said rotor, said chamber being provided with a plurality of discharge openings equal in number to said blades, and through which the abrasive is fed into the spaces between said blades.

6. In an abrading apparatus, a rotor having a plurality of abrasive propelling blades provided thereon, a centrally located chamber mounted for synchronous rotation with said rotor, means for introducing abrasive into said chamber and allowing it to build up centrifugally on the inner surface thereof, and means for deflecting abrasive from the chamber onto said blades adjacent the inner ends thereof at a predetermined point in the rotation of the rotor, said chamber being provided with a plurality of discharge openings equal in number to said blades, forwardly of each blade, through which the abrasive is fed to the

latter, and the portions of said chamber between said openings preventing the discharge of abrasive at other points in the spaces between said blades.

5. In an abrading apparatus, a rotor having a plurality of abrasive propelling blades thereon, a centrally located and substantially cylindrical chamber closed at one end and open at the opposite end and mounted for rotation with said rotor substantially concentric with the axis of said rotor, the closed end of said chamber being adjacent said blades, the side wall of said chamber adjacent said blades being provided with a series of openings equal in number to the number of blades on said rotor, means to feed abrasive into the open end of said chamber and allow it to build up centrifugally on the inner surface thereof, and means to deflect abrasive in said chamber through said openings and onto said blades adjacent the inner ends thereof at a predetermined point in the rotation of said rotor.

8. In an abrading apparatus, a rotor having a plurality of abrasive propelling blades thereon, a centrally located and substantially cylindrical chamber closed at one end and open at the opposite end and mounted for rotation with said rotor substantially concentric with the axis of said rotor, the closed end of said chamber being adjacent said blades, the side wall of said chamber adjacent said blades being provided with a series of openings equal in number to the number of blades on said rotor, means to feed abrasive into the open end of said chamber and allow it to build up centrifugally on the inner surface thereof, means to deflect abrasive in said chamber through said openings and onto said blades adjacent the inner ends thereof at a predetermined point in the rotation of said rotor, and means to prevent the discharge of abrasive through said openings at points other than said predetermined point.

9. In an abrading apparatus, a rotor having a plurality of abrasive propelling blades thereon, a centrally located and substantially cylindrical chamber closed at one end and open at the other end and mounted for rotation with said rotor substantially concentric with the axis of said rotor, the closed end of said chamber being adjacent said blades, the side wall of said chamber adjacent said blades being provided with a series of openings equal in number to the number of blades on said rotor, means to feed abrasive into the open end of said chamber and allow it to build up centrifugally on the inner surface thereof, and means to deflect abrasive in said chamber through said openings and onto said blades adjacent the inner ends thereof at a predetermined point in the rotation of said rotor comprising a substantially cylindrical element mounted on said feed spout within said chamber and a helical flange mounted on the outside of said element with one end terminating adjacent the openings in the side wall of said chamber.

10. The combination claimed in claim 9 wherein said flange increases in diameter from a point adjacent the open end of said chamber to a point adjacent the openings in the side wall of said chamber.

11. The combination claimed in claim 9 wherein a second flange of substantially no pitch is provided around a portion of said element adjacent said openings to prevent the discharge of abrasive through said openings except at the predetermined point in the rotation of said rotor.

12. In an abrading apparatus, a rotor having

a plurality of abrasive propelling blades thereon, a centrally located and substantially cylindrical chamber closed at one end and open at the opposite end and mounted for rotation with said rotor substantially concentric with the axis of said rotor, the closed end of said chamber being adjacent said blades, the side wall of said chamber adjacent said blades being provided with a series of openings equal in number to the number of blades on said rotor, means to feed abrasive into the open end of said chamber, the chamber at said open end being partially closed to enable the abrasive to be built up to an angle of repose facing toward the closed end of said chamber, and means to deflect abrasive in said chamber through said openings and onto said blades adjacent the inner ends thereof at a predetermined point in the rotation of said rotor.

13. In an abrading apparatus, a rotor having a plurality of abrasive propelling blades provided thereon, the inner ends of said blades being spaced apart to define a central opening, a shaft in said central opening fixed to said rotor to rotate therewith, a substantially cylindrical chamber fixed to the end of said shaft to rotate therewith, said chamber having an open end adjacent the inner ends of said blades whereby the edge of the wall of said chamber at said open end constitutes a discharge edge for abrasive, means to feed abrasive into said chamber, and means in said chamber to deflect abrasive therefrom over said discharge edge onto the inner ends of said blades at a predetermined point in the rotation of said rotor.

14. In an abrading apparatus, a rotor having a plurality of abrasive propelling blades provided thereon, the inner ends of said blades being spaced apart to define a central opening, a shaft in said central opening fixed to said rotor to rotate therewith, a substantially cylindrical chamber fixed to the end of said shaft to rotate therewith, said chamber having an open end adjacent the inner ends of said blades whereby the edge of the wall of said chamber at said open end constitutes a discharge edge for abrasive, the opposite end of said chamber being formed with an inturned flange whereby abrasive supplied to said chamber when the latter is rotating builds up on the walls thereof by reason of centrifugal force with an angle of repose inclined toward said discharge edge, means to feed abrasive into said chamber, and means in said chamber including a stationary helical blade to deflect abrasive therefrom over said discharge edge onto the inner ends of said blades at a predetermined point in the rotation of said rotor.

15. In an abrading apparatus, a rotor having a plurality of abrasive propelling blades provided thereon, the inner ends of said blades being spaced apart to define a central opening, a shaft in said central opening fixed to said rotor to rotate therewith, a substantially cylindrical chamber fixed to the end of said shaft to rotate therewith, said chamber having an open end adjacent the inner ends of said blades whereby the edge of the wall of said chamber at said open end constitutes a discharge edge for abrasive, means to feed abrasive into said chamber, means in said chamber to deflect abrasive therefrom over said discharge edge onto the inner ends of said blades at a predetermined point in the rota-

tion of said rotor, and means adjacent the outer periphery of said discharge edge to prevent prematurely discharged abrasive from being discharged onto said blades at other than said predetermined point.

16. In an abrading apparatus, a rotor having a plurality of abrasive propelling blades provided thereon, the inner ends of said blades being spaced apart to define a central opening, a shaft in said central opening fixed to said rotor to rotate therewith, a substantially cylindrical chamber fixed to and extending over the end of said shaft to rotate therewith, said chamber having an open end adjacent the inner ends of said blades whereby the edge of the wall of said chamber at said open end constitutes a discharge edge for abrasive, means to feed abrasive into said chamber, a stationary housing, and a helical blade supported on said housing concentrically of said shaft and within said chamber to deflect abrasive therefrom over said discharge edge onto the inner ends of said blades at a predetermined point in the rotation of said rotor.

17. In abrading apparatus, a rotor having a plurality of outwardly extending abrasive propelling blades of a length to dispose their outer ends sufficiently radially distant from the axis of the rotor to propel the abrasive at an abrading velocity, a centrally located and substantially cylindrical feed chamber mounted for rotation with said rotor with the axis thereof substantially in alignment with the axis of said rotor, means for supplying abrasive in one general direction into one end of said chamber and allow it to build up centrifugally in the same general direction on the inner surface thereof, and means for deflecting a portion of the accumulated abrasive towards an opposite end of the chamber and from the feed chamber onto said blades adjacent the inner ends thereof at a predetermined point in the rotation of said rotor.

18. In abrading apparatus, a rotor having a plurality of abrasive propelling blades provided thereon, a centrally located hollow cylindrical member mounted for rotation with said rotor, means for introducing abrasive into said cylindrical member and allowing the abrasive to build up centrifugally on the inner surface thereof, said cylindrical member having a peripheral opening therein forwardly of each blade, and means for deflecting a portion of the accumulated abrasive for movement through said openings onto said blades adjacent the inner ends thereof at a predetermined point in the rotation of said rotor.

19. In abrading apparatus, a rotor having a plurality of abrasive propelling blades provided thereon with the inner ends thereof defining a central opening, a support extending axially through said central opening and fixed to said rotor to rotate therewith, a substantially cylindrical feed chamber carried by an outer portion of said support to rotate therewith, said chamber having a discharge edge adjacent the inner ends of said blades, means for supplying abrasive into said feed chamber, and means in said feed chamber to deflect abrasive therefrom over said discharge edge onto the inner ends of said blades at a predetermined point in the rotation of said rotor.

WALTER L. KEEFER.
